UNITED STATES PATENT OFFICE.

ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

SHOE-SOLE.

1,190,320.

Specification of Letters Patent. Patented July 11, 1916.

Application filed November 16, 1912. Serial No. 731,893.

To all whom it may concern:

Be it known that I, ADAM H. PRENZEL, citizen of the United States, residing at Halifax, in the county of Dauphin and State of Pennsylvania, have invented certain new and useful Improvements in Shoe-Soles, of which the following is a specification, reference being had therein to the accompanying drawing.

10 This invention relates to an improved shoe sole.

The present invention relates more particularly to a sole intended for use in the manufacture of shoes, the uppers of which are provided with outwardly turned sole attaching portions, and one of the objects of the present invention is the provision of an improved shoe sole of this character which comprises, as an integral part thereof, 20 a welt strip for securing the outwardly turned portion of the upper to the sole.

A further object of the present invention is so to construct a sole of this character, having a welt strip, as to prevent the formation of a thick bulky sole when the shoe is manufactured, and to facilitate the finishing of the sole of the shoe when the shoe is completed. The novel process of making shoes herein disclosed is not claimed herein 30 but is claimed in my co-pending application Serial No. 731,894, filed of even date herewith, upon which application Letters Patent No. 1,159,083 were granted November 2, 1915, while similarly the novel shoe herein 35 disclosed is not claimed herein but is claimed in my co-pending application Serial No. 731,892, also filed of even date herewith.

In the drawings, wherein a convenient embodiment of the invention is illustrated, 40 and wherein like characters of reference refer to similar parts in the several views, Figure 1 is a perspective view of a shoe sole constructed according to the present invention; Fig. 2 is a cross section through the 45 sole shown in Fig. 1, and, Fig. 3 is a detail section showing the sole and the parts connected to and associated therewith.

Referring now more particularly to the drawings, A designates an outer sole which 50 is provided with a recess or channel a extending around the front portion thereof, the ends of said channel terminating adjacent the heel portion of the outer sole. In forming the channel a in the outer sole A 55 the material of the outer sole is so cut that

said channel will be provided with an abrupt or substantially vertical inner shoulder a', and the bottom surface of said channel will be inclined downwardly from the inner edge to the outer edge of the channel. Cutting 60 the outer sole in this manner to form the channel a therein also provides a strip which is provided with a transversely inclined lower surface, and in forming the sole the strip which is removed from the upper surface thereof to provide a channel a therein is severed from the sole at one end only so that there is provided a welt strip A' which is integral with the sole and is connected thereto at one end only. A portion of the 70 outer edge of the welt strip thus formed is removed so that such strip is of slightly less width than the channel a which is formed in the sole, and to simplify the manufacture of the sole the outer portion of such welt 75 strip is conveniently removed simultaneously with the cutting out of the strip from the sole. The free end of the welt strip is conveniently severed from the outer sole in such a manner as to provide the same with a 80 beveled under surface.

In using the sole as above described in the manufacture of shoes, an upper is used which has an outwardly turned lower edge which is adapted to fit within the channel a 85 of the sole, and after the upper has been so positioned, the welt strip is positioned over the outwardly turned portion of the upper and the welt strip, outer sole and the interposed portion of the upper are united by 90 stitching or other suitable fastening means. The welt strip is secured in position so that the inner edge thereof will hold the upper firmly against the inner shoulder a' of the channel a in the outer sole, and when the 95 welt strip is so secured, the outer edge thereof will lie flush with the outer edge of the outer sole by reason of the fact that just so much of the outer edge of the welt strip is removed as will provide space for the thickness of the material which is to be secured between the inner edge of said welt strip and the shoulder a' of the channel a in the outer sole.

As has been before stated, the welt strip 105 A' is cut from the outer sole A in such a manner as to provide a beveled under surface for the welt strip, the inner edge of such strip being of less thickness than the outer edge thereof. This construction prevents the 110

formation of a sole which will have a bulky appearance when the welt strip is secured thereto with the outer edge thereof flush with the outer edge of the sole, since the portion of the welt strip which is removed to provide space for the accommodation of the out-turned portion of the upper is the thickest portion of the strip. Moreover the movement of the reduced welt strip toward the outer edge of the sole lowers it at the same time owing to the inclination of the channel and thus brings its surface substantially flush with the upper surface of the sole.

While a convenient embodiment of the invention is illustrated in the accompanying drawings, it will be understood that many changes may be made to the particular form and construction therein shown without departing from the spirit and scope of the invention as defined in the appended claims.

I claim:-

1. As a new article of manufacture, a shoe sole for stitch-down shoes provided with a welt strip having one of its ends integrally connected thereto, said welt strip being otherwise unconnected to said sole.
2. As a new article of manufacture, a shoe sole provided with a channel extending along the edge thereof and provided with a welt strip having one of its ends integrally connected thereto at one end of the channel formed therein, said welt strip being otherwise unconnected to said sole.

3. As a new article of manufacture, a shoe sole for stitch-down shoes provided with a channel extending along the edge thereof and provided with a welt strip of less width than the channel in the sole and having one of its ends integrally connected to the sole at one end of the channel formed therein, said welt strip being otherwise unconnected to said sole.

4. As a new article of manufacture, a shoe sole provided with a channel, which extends along the edge thereof and which has an abrupt inner shoulder and a bottom surface inclined downwardly to the outer edge thereof, and provided with a welt strip which has one of its ends integrally connected to the sole at one end of the channel formed therein and is otherwise unconnected to said sole, said welt strip being provided with a bottom surface inclining downwardly from the inner to the outer edge thereof, being of less width than the channel in the sole, and when located with its outer edge flush with the outer edge of the sole, being of less thickness than the depth of the portion of said channel which it overlies.

In testimony whereof I affix my signature in presence of two witnesses.

ADAM H. PRENZEL.
